MACHINE AND METHOD FOR PERFORATING PLASTERBOARD

Thomas H. Heath, Enterprise, Kans., assignor to
The J. B. Ehrsam & Sons Mfg. Co., Enterprise,
Kans., a corporation of Kansas

Application September 8, 1938, Serial No. 228,950

14 Claims. (Cl. 164—89)

The present application relates to a machine for perforating plaster board and to a method which may be performed either by said machine or by other means.

In recent years, the use of plaster board as a substitute for wooden or metal lath has come into considerable prominence. It is essential, however, if plaster is to be subsequently spread on board of this character in finishing a wall, to provide anchoring means; and it has become customary to perforate the board at frequent intervals to provide such anchoring means.

According to present commercial practice, the plaster board is formed, by machines, by sandwiching a fluent plastic, such as gypsum plaster, between two fibrous binders, paper being usually used for the binders. The plastic usually takes a preliminary set very promptly after the composite sheet is formed; and then more gradually assumes a permanent and final set. Even after the plastic has assumed its final set, there is considerable excess moisture in the sheet; and this is removed by a drying operation.

The sheet, according to general practice before my invention, is usually cut into suitable lengths, before the plastic takes its final set, although sometimes the material is cut after it has set. The severed lengths of board are then passed through a drier to expel excess moisture; and after drying, they are stacked into bundles. These bundles of cut lengths are then perforated by drills, usually gang drills, which form the necessary anchoring perforations. Obviously, the drills penetrating through the hard plaster of the boards, form a considerable amount of dust; and some quantities of that dust are retained in the rough walls of the perforations. When the boards are then put in place in a building operation, that dust tends to fall out, to the considerable irritation and discomfort of the operator. Furthermore, it has been found in practice that the perforations so formed in some of the boards are likely to be rough and nonuniform; and that the paper binders are likely to be torn in the drilling operation. Still further, of course, drills which are used on dried or semi-dried plaster board soon lose their cutting sharpness.

It is the primary object of the present invention to provide a method of perforating plaster board by punching the board before the plaster takes its final set; and to provide a machine capable of carrying out that method. I am aware of the fact that it has heretofore been attempted to provide such a method and such a machine,

and that patents have been issued on machines which are alleged to carry out such a method. Some of those machines have been put into commercial use, however, and have been found to be commercially entirely impracticable for various reasons.

It will be readily appreciated, however, that if a commercially practical method of perforating the boards prior to setting of the plaster can be provided, and if a machine can be constructed which will efficiently carry out that method, considerable savings may be effected in the production of perforated plaster board lath. In the first place, it is obvious that considerably less power will be required to punch through a plastic mass retained between paper binders than is required to drill through a corresponding mass of set plaster. In the second place, the drying operation is materially facilitated, shortened, and cheapened if the perforations are formed in the board before the drying step; since the removal of slugs at frequent intervals throughout the body of the board gives the drying air an enormously larger surface upon which to work. Furthermore, the difficulties with dust, not only in the manufacturing plant but also in the handling of the boards and in the application thereof to building installations, are substantially eliminated. Still further, the holes formed by punching through a plastic mass are found to be considerably more uniform, smoother, and less subject to deformation.

Thus, a further object of the invention is to attain the above advantages through providing a method of, and machine for, perforating plaster board in the unset condition by punching.

A still further object of the invention is to provide a machine which is useful not only in the above manner, but also in the perforating of plaster board after the plaster has taken its final set. It has been found that the machine of the present application may be so used efficiently; and that many of the advantages above set forth are thereby attained. Further objects of the invention will appear as the description proceeds.

To the accomplishment of the above and related objects, my invention may be embodied in the forms illustrated in the accompanying drawings, attention being called to the fact, however, that the drawings are illustrative only, and that change may be made in the specific constructions illustrated and described, or in the specific steps stated, so long as the scope of the appended claims is not violated.

Fig. 1 is a flow sheet, diagrammatic in char-

acter, illustrating the progress of plaster board from the time when it leaves the forming machine to the time when it is ready to be shipped;

Fig. 2 is a plan of the specific machine which performs the punching operation;

Fig. 3 is a side elevation thereof;

Fig. 4 is an end view of the punching stage, parts being broken away for clarity of illustration;

Fig. 5 is a somewhat enlarged fragmental longitudinal section taken substantially on the line 5—5 of Fig. 4 and looking in the direction of the arrows;

Fig. 6 is an enlarged fragmental section showing the brake and operating means therefor;

Fig. 7 is an enlarged view of the Geneva movement utilized in the machine;

Fig. 8 is an enlarged fragmental section of a portion of the roller chain conveyor;

Fig. 9 is an enlarged section, fragmental in character, showing one of the punches with its associated die and the header whereby it is carried;

Fig. 10 is a fragmental end elevation of a somewhat modified form of machine;

Fig. 11 is a side elevation of the machine illustrated in Fig. 10;

Fig. 12 is a fragmental transverse section showing an actuating eccentric;

Fig. 13 is a more or less diagrammatic view of a plaster board forming machine associated with the feed conveyor leading to the machine of Fig. 2;

Fig. 14 is a conventional wiring diagram illustrating one manner in which the controlling solenoid may be actuated; and

Fig. 15 is an enlarged fragmental sectional view of a detail of construction.

Referring more particularly to Fig. 1, it will be seen that I have illustrated a belt conveyor 20 suitably driven by shafting 21 which in turn is driven through a variable speed transmission 22, preferably of the "Reeves" type, by a motor 23. The conveyor 20 receives the freshly formed board from the forming machine and supports it while the plaster takes a preliminary set, thereafter discharging the sheet onto a live roll conveyor 25 suitably driven, by mechanism illustrated at 24, from the shafting 21.

The said forming machine is illustrated in Fig. 13 and consists of a table 201 upon which is supported a portion 202 of a continuous sheet of paper 203 fed to said table from a storage roll 204 and threaded below a guiding roll 205. A plaster spreading mechanism 206 is supported above the table 201 and operates, in a known manner, to spread a layer of fluent plaster uniformly over the upper surface of the portion 202 of the paper strip as said strip passes below the mechanism 206.

As the paper strip leaves the table 201, it finds support upon the lower one 207 of a pair of presser rolls, the upper one 208 of said rolls being positioned adjacent the roll 207. A second strip of paper 209 is threaded over a guide roll 210 and under the presser roll 208 as said strip leaves a second storage roll 211. The composite strip consisting of the paper sheet 203, the fluent plaster deposited by the mechanism 206, and the upper paper strip 209 is discharged from the presser rolls upon the belt conveyor 20 above mentioned.

A chain 26 connects the conveyor 25 to drive a shear 27 which is automatically operated to cut the advancing sheet into suitable lengths.

To this point, the flow sheet represents standard commercial practice.

At 28, I have indicated diagrammatically an accelerated live roll conveyor section, the length 5 of which is considerably greater than is indicated in the drawings. The cut lengths of board, leaving the shear 27, are seized upon by the conveyor section 28 and rapidly advanced to a conveyor section 29, thus being advanced considerably beyond the advancing end of the continuous sheet on the conveyor section 25. At 30, is indicated the punch mechanism per se, from which a conveyor section 31 withdraws the perforated board sections to deposit them upon a transfer table 32. Thence, the board sections go onto a tipple table 33 from which they are loaded, at 34, to pass through a drier 35 which is supplied, through a flue 37, with air heated at 36 and driven into the drier by a fan indicated at 38. From the drier, the board lengths are removed in condition to be shipped.

Referring, now, to Figs. 2 to 9 inclusive, it will be seen that I have illustrated in detail the conveyor section 29, the punch mechanism 30, and the conveyor section 31. This machine may preferably be built as a unit, comprising end standards 39 and 40 supporting a main frame 43. Said standard 39 provides a journal mounting for a shaft 41 about the axis of which is journaled one end of a frame 42 comprising the frame for the conveyor section 31. Similarly, the standard 40 provides a journal mounting for a shaft 44 about the axis of which is journaled one end of a frame 45 upon which is mounted the conveyor 29. The shaft 41 supports a pair of sprockets 46, and a second pair of sprockets 47, respectively positioned in the planes of the sprockets 46, are mounted upon the machine frame. Similarly, the shaft 44 carries a pair of sprockets 48, and a further pair of sprockets 49, positioned respectively in the planes of the sprockets 48, are mounted upon the machine frame. A roller chain conveyor 50 is threaded around the sprockets 46, 48, 49, and 47, and said chain conveyor carries, at suitably spaced intervals, transversely extending stop elements, of which the elements 51 and 52 (see Fig. 3) are representative. The function of these stop elements will be explained hereinafter.

The punch mechanism per se is supported upon standards 53, which support a transversely extending table 54 provided with a plurality of perforations in which are mounted dies 55. A stripper plate 56 is adjustably positioned in parallelism with said table 54.

In suitable bearings on the standards 53 above the table 54 is journaled a main shaft 57 provided, adjacent its opposite ends, with two eccentric portions 57" like that illustrated in Fig. 12 upon which are respectively journaled the end bearings 58 and 59 (see Fig. 2) of connecting rods 60 and 61, the lower ends 62 and 63 being suitably journaled upon trunnions supporting a head 64 suitably guided in the uprights 53. Said head 64 carries two hollow headers 65 provided with inlet ports 66 to which is connected a suitable source of fluid under pressure. A plurality of punches 67 are carried by the head 64, each of said punches being formed with a cavity in its leading end, and said cavity being in communication with the interior of a header 65. The punches and dies used in the present machine are preferably of the type disclosed in the patent to William J. Ehrsam, 2,182,744, granted December 5, 1939.

As is clearly shown in Fig. 5, the header inlet ports 66 are connected, by pipes 120 and suitable connections, with the outlet port valve 125, to the inlet port of which is connected a flexible conduit 121 connected to a source of fluid under pressure which may preferably be compressed air. The valve 125 herein illustrated is the type which is resiliently held normally closed, and which may be opened against its resilient tendency by moving the stem 126 upwardly. A link 127 supports one end of a lever 122 positioned to engage the stem 126; and a strap 123, which may be carried by a member 124 on the machine frame, is located in the path of the opposite end of said lever 122.

A bracket 68 carried by the uprights 53 or otherwise suitably mounted carries a motor 69 with which is preferably associated a reduction gearing 69', the output shaft of which carries a sprocket or pulley 70 connected by a chain or belt 71 with a sprocket or pulley 72 carried by a flywheel 73 loosely mounted upon the shaft 57. A clutch 74, which is preferably of the well known Hilliard single-revolution type, is provided for optionally providing a driving connection between the flywheel 73 and sprocket 72 and the shaft 57.

Suitably supported upon the uprights 53 is a second shaft 75 carrying a Geneva wheel 76 which is illustrated in some detail in Fig. 7. The shaft 57 carries a pinion 77 having a single tooth 78 cooperable with the slots 79 of the Geneva wheel 76. Said pinion 77 is, of course, provided with a hub 77' suitably shaped to engage within the surfaces 79' of the Geneva wheel at times to hold said wheel against rotation, and cut away to release said wheel rotation when the tooth 78 engages in one of the slots 79. This construction is, of course, merely standard Geneva movement construction.

The shaft 75 carries a sprocket or pulley 80 which is connected, by a chain or belt 81, to drive a sprocket or pulley 82 on the shaft 41. It will thus be seen that the construction above described provides for intermittent driving of the roller chain conveyor above described, upon continuous rotation of the shaft 57.

An advantageous arrangement of perforations in plaster board lath contemplates the provision of perforations spaced, both longitudinally and transversely of the board, four inches from each other. In the illustrated machine, the head 64 carries two longitudinally spaced series of punches 67, the two series being spaced four inches from each other, and each punch of each series being spaced four inches from its next adjacent punch. The conveyor-driving mechanism is, therefore, proportioned to shift the conveyor eight inches after each reciprocation of the head 64; or, in other words, upon each rotation of the shaft 57.

In Fig. 6, I have illustrated brake mechanism, indicated generally by reference numeral 83 and comprising two shoes engaging a drum carried by the shaft 57, said shoes being urged into engagement with said drum by a spring 84. Associated with said brake mechanism is a solenoid 85 the core 86 of which is operatively connected to a lever 87 which, upon oscillation in a counter-clockwise direction from the illustrated position, will cause separation of the brake shoes to release the shaft 57 for rotation. Said core 86 is also positioned to engage, upon downward movement, a finger 88 mounted on a rock shaft 89 which is operatively connected to actuate the

clutch 74. Thus, upon energization of the solenoid 85, the brake 83 is released and the clutch 74 is engaged.

Relay mechanism is provided for energizing the solenoid 85. A control element 90 is suitably mounted upon the machine frame and is provided with a finger 91 which is positioned in the path of material advancing over the conveyor 29 toward the table 54. A similar control member 92 is provided with a finger 93 which is positioned in the path of material leaving the table 54 on the conveyor 31. Movement of the finger 91 toward the right as a result of engagement with material on the conveyor 29 closes a circuit 15 from a suitable source of current 200 through wire 201, switch terminal 202, switch terminal 203 moved by the finger 91, wire 204, terminal 205 of solenoid 85, coil of solenoid 85, terminal 206, and wire 207 back to the source of current, to energize the solenoid 85. Similarly movement of the finger 93 toward the right closes a circuit from current source 200 through wire 208, switch terminal 209 controlled by the finger 93, switch terminal 210, wire 211, wire 204, solenoid terminal 205, solenoid coil, terminal 206, and wire 207 back to the power source, to energize the solenoid 85. Thus, so long as either of the fingers 91 or 93 is engaged by material moving through the machine, the solenoid 85 will remain energized and the core 86 thereof will hold its depressed position in which the brake 83 is released and the clutch 74 is engaged.

The operation of the illustrated mechanism is as follows. A board length severed from the main sheet by the knife 27, is rapidly advanced by the accelerator conveyor section 28 to the conveyor section 29; and the operation of the live roll conveyor 25 carries that length upwardly into engagement with the stop 52. Just before the board length strikes the stop 52, it engages the finger 91 to energize the solenoid 85. The motor 69 is continuously operating so that, when the solenoid 85 is energized and the brake 83 is released and the clutch 74 engaged, the shaft 57 begins to rotate. Thereby, the Geneva wheel 76 is advanced one step to advance the roller chain conveyor eight inches. Such movement of the roller chain conveyor brings the stop 51 into engagement with the trailing end of the board length, so that, thereafter, the board length will partake of further movement of the roller chain conveyor. Continued rotation of the shaft 57 will reciprocate the head 64 to drive the punches 67 through the board length to make two series of perforations therein.

As the punches are moved downwardly, each of them will first engage the board with the extremities of its teeth (see Fig. 9) which penetrate the top paper layer in a peripheral series of pin point perforations; and as the punches move on down through the board, the sharpened lateral edges of the teeth cut through the board with a slicing or draw-cut knife-like action; the slicing action of each tooth taking place on lines angling 60 toward the pin point perforations made by the adjacent teeth and toward the lower surface of the board. This action of each tooth continues, as the punches move downwardly, until each punch has penetrated entirely through the board.

The type of slicing here described minimizes deformation of the layer of unset plaster between the liner sheets, and can be carried out by any one of a plurality of mechanisms; but I have found that the punch illustrated is one form of

device by which my perforating process may be effectively accomplished.

As said punches penetrate the board, the lever 122 engages the stop 123 to lift the stem 126, thereby opening valve 125 to release a charge of air to the headers 66 to force the pieces of removed material out of the punch cavities, whence they are discharged through the dies 55.

As the punches are withdrawn by upward movement of the head 64, the lever 122 leaves the stop 123, thus permitting the valve 125 to return, under its own resilient tendency, to closed position. At the same time, the tooth 78 engages the next notch 79 in the Geneva wheel 76 to advance the roller conveyor and the board length one more step, whereafter the head 64 is again moved downwardly to drive the punches 67 through the board length to form two more series of perforations. This intermittent operation continues, the parts being so coordinated that the punches are engaged with the board only during times when the board is stationary, and that the board is moved only at times when the punches are entirely withdrawn therefrom, until the entire board length has passed through the punching stage and has been carried beyond the finger 93. As the trailing end of the board length passes the finger 93, the stop 52 is carried down around the sprockets 46 to release the leading end of the board length, which then comes under the influence of the live roll conveyor 31, and is moved onward to the transfer table 32.

While, as has been said, a great deal of perforated plaster board lath is manufactured and used at the present time, a great deal of unperforated plaster board is also used. It is desirable, therefore, so to construct a perforating mechanism that the manufacturing line may be used in the production of unperforated plaster board. I have so designed the present machine as to make it possible to by-pass the advancing board around the punching stage. As has been stated, the frames 42 and 45 are journaled upon the axes of the shafts 41 and 44, respectively. The ends of said frames adjacent the punching stage are supported respectively upon toggles 94 and 96, each of which is operable by a lever 95 or 97. In Fig. 3, I have illustrated in dotted lines, the positions of the toggles 94 and 96, the levers 95 and 97, and the frames 42 and 45, in which the board is by-passed around the punching stage. With the frames 42 and 45 in the dotted line positions, the advancing board remains under the influence of the live roll conveyors 29 and 31 and passes beneath the table 54, so that the fingers 91 and 93 are not engaged and the solenoid 85 is not energized.

In Figs. 10 and 11 I have illustrated a modified form of machine which dispenses with the roller chain conveyor. In that machine, uprights 53' provide a journal mounting for a main shaft 57' in all respects identical with the shaft 57. The sprocket 72' is driven by the chain 71' from the gear reduction output shaft 70'; and carries a single toothed pinion 78' cooperating with a Geneva wheel 76' which drives a sprocket or pulley 80' which, through a chain or belt 81', drives a sprocket or pulley 110 mounted upon a countershaft 111. Said countershaft carries a sprocket 112 which, through a suitable chain, drives a sprocket 113 on a shaft 114 carrying a feeder roll 115. Said feeder roll cooperates with a floating roll 116 on a shaft 117, the bearings 128 for which are supported on springs 129. A trip head 130 is hinged at 131 to an element 135

fast on the machine frame 53' and carries adjacent its free edge a tubular trip rod 132 adapted to be engaged by one or more trip latches 133, each of which is slidably mounted in the element 135. A spring 134 is sleeved on each of said latches 133 to hold the same resiliently against upward movement and to exert a predetermined downward pressure upon the roll bearings 128 through the trip head 130, all as is already shown in Fig. 11. The springs 134 are backed by nuts 136, adjustably threaded on the elements 133, so that their effect upon the bearings 128 may be varied.

A suitable chain drive connects another sprocket (not shown) on the shaft 114 to drive a sprocket 113' on shaft 114' carrying a feeder roll 118 cooperating with a floating roll 119 at the other side of the punching station; and said roll 119 is mounted in the manner of the roll 116; having associated therewith bearings 137, springs 138, a trip head 139, hinged at 140 to an element 144 and carrying a tubular trip rod 141 engaged by trip latches 142 held by springs 143 backed by nuts 145.

The normal positions of the rolls 116 and 119 with respect to the rolls 115 and 118 may, of course, be varied by adjustment of the nuts 136 and 145; and said rolls 116 and 119 may be moved entirely out of cooperative relation with the rolls 115 and 118 by releasing the trips 133 and 142. The tubular rods 132 and 141 are so shaped (see Fig. 15) that when they are rotated about their respective axes by suitable cranks or handles (not shown) they will assume, at different points, positions in which they may be engaged by the trips 133 and 142, or other positions in which they may not be so engaged but will be released therefrom.

Control elements 90' and 92' are positioned adjacent the respective pairs of feeder rolls. Material fed to the rolls 115 and 116 by any suitable means such as the accelerator, live roll section 28, contacts the control element 90' to energize the solenoid which throws the shaft 57' into operation; and the operation of the embodiment of Figs. 10 and 11 is closely similar to that of the embodiment previously described, except that the material is advanced through the punching stage by the feed rolls instead of by the roller chain conveyor of the form previously described.

In Fig. 8 is disclosed the means for supporting the roller chain conveyor. Suitable frame members 98 support rails 99 and 100 between which the roller 101 of the conveyor chains are guided.

I claim as my invention:

1. Mechanism for perforating plaster board comprising a table, means for intermittently advancing a section of plaster board across said table, a header, a gang of punches carried by said header, each of said punches being formed with a cavity in its leading end for receiving a punched-out slug of plaster board material, said cavity communicating with said header, means for reciprocating said header, means for supplying fluid under pressure to said header and so to said cavities, and means coordinating said board-advancing means, said header-reciprocating means, and said fluid-supplying means to reciprocate said header only during inactivity of said board-advancing means and to actuate said fluid-supplying means only after completion of board-penetrating movement of said header.

2. For association with a continuously operated plaster board forming machine, means for cut-

ting and perforating the plaster board as it emerges continuously from said machine, comprising means positioned in the path of the emerging stream of unset plaster board and operative to cut such plaster board into lengths, means for rapidly moving each severed length away from said cutting means, a table, means receiving the severed lengths from such moving means and operative to advance the same intermittently over said table, a reciprocating punch, and means coordinated with said advancing means to reciprocate said punch to force the same through such length while the latter is stationary.

3. Punching mechanism comprising a table supporting a hollow die, a punch mounted for reciprocating cooperation with said die, conveyor means positioned to feed material to and across said table between said punch and said die, a shaft operatively connected to reciprocate said punch, power means, electric means for connecting said power means to drive said shaft, an energizing circuit for said electric means including two normally open switches connected in parallel, means positioned adjacent said table in the path of oncoming material and engageable by such material to close one of said switches, means positioned adjacent said table in the path of material leaving said table and engageable by such material to close the other of said switches, and means operable upon rotation of said shaft to drive said conveyor means intermittently.

4. The combination with a machine for producing plaster board and means for cutting the board emerging from such machine into lengths, of perforating means comprising a frame carrying a live-roll conveyor mounted to receive such board lengths, a table carrying a die positioned to receive board lengths discharged from said conveyor, a second conveyor mounted on said frame and carrying stop elements arranged to engage said board lengths to control the same against the tendency of said live-roll conveyor, a reciprocating punch, means for driving said punch, and means for driving said second conveyor intermittently, said last-named means being coordinated with said punch-driving means to hold said second conveyor against movement during engagement of said punch with a board length.

5. The combination with a machine for producing plaster board and means for cutting the board emerging from such machine into lengths, of perforating means comprising a frame carrying a live-roll conveyor mounted to receive such board lengths, a table carrying a die positioned to receive board lengths discharged from said conveyor, a second conveyor associated with said frame and carrying stop elements arranged to engage said board lengths to control the same against the tendency of said live-roll conveyor, a reciprocating punch, means for driving said punch, means for driving said second conveyor intermittently, said last-named means being coordinated with said punch-driving means to hold said second conveyor against movement during engagement of said punch with a board length, a second frame carrying a live-roll conveyor mounted to receive board lengths discharged from said table, each of said frames being pivotally mounted at its end remote from said table, and means operable to shift said frames into and out of operative association with said table, said live-roll conveyors being positioned, when said frames are moved out of such association, to cooperate to carry board lengths continuously past said

table without bringing them into operative association with said punch.

6. Punching mechanism comprising a table carrying a hollow die, a reciprocating punch operatively associated therewith, a frame carrying a live-roll conveyor pivotally mounted at its end remote from said table and positionable to feed material to said table, a second conveyor carried by said frame and provided with stop elements to control such material independently of said live-roll conveyor, a motor for driving said punch and said second conveyor independently of said live-roll conveyor, means positioned adjacent said table and engageable by material moving over said frame to control operation of said punch and conveyor by said motor, and means for shifting said frame about its pivot to a position removed from said last-named means to carry material past said table.

7. Punching mechanism comprising a table carrying a hollow die, a reciprocating punch operatively associated therewith, a frame carrying a live-roll conveyor pivotally mounted at its end remote from said table and positionable to feed material to said table, a second conveyor carried by said frame and provided with stop elements to control such material independently of said live-roll conveyor, a motor connected to reciprocate said punch, means driven by said motor for driving said second conveyor intermittently, said last-named means being coordinated with said punch to drive said conveyor only while said punch is out of engagement with material on said table, means positioned adjacent said table and engageable by material moving over said frame to control operation of said punch and conveyor by said motor, and means for shifting said frame about its pivot to a position removed from said last-named means to carry material past said table.

8. The method of perforating plaster board or the like which comprises the steps of moving the plaster board intermittently, while the plastic material is in unset condition, over a supporting table provided with a die, and penetrating such board, while it is in static condition, with a punch cooperating with said die.

9. The method of perforating plaster board or the like which comprises the steps of moving the plaster board intermittently, while the plastic material is in unset condition, over a supporting table provided with a die, and penetrating such board, while it is in static condition, with a punch moving in a straight line and cooperating with said die.

10. The method of perforating unset plaster board or the like which comprises the steps of supporting the board on a perforated surface, forming pin-point perforations in that surface of the board remote from said supporting surface, said pin-point perforations being spaced from each other and arranged to coincide substantially with the perimeter of the perforation in such supporting surface, and thereafter slicing entirely through the board with a knife-like action from each of said pin-point perforations on lines angling toward each other and toward said supporting surface.

11. In combination, power means, a punch, a shaft operatively connected to reciprocate said punch, means including a clutch connecting said power means to drive said shaft, a brake associated with said shaft, a conveyor for moving material past said punch in operative relation thereto, means driven by said shaft for driving said

conveyor intermittently, an electric relay comprising means operable, upon actuation of said relay, to release said brake and to engage said clutch, an energizing circuit for said relay, and means positioned in the path of material on said conveyor and dominating said circuit.

12. In combination, power means, a punch, a shaft operatively connected to reciprocate said punch, means including a clutch connecting said power means to drive said shaft, a brake associated with said shaft, a pair of feeder rolls positioned adjacent said punch and operative to feed material into cooperative relation to said punch, means driven by said shaft for driving said rolls intermittently, an electric relay comprising means operable, upon actuation of said relay, to release said brake and to engage said clutch, an energizing circuit for said relay, means for feeding material to said rolls, means for withdrawing material from said rolls, and means engageable by such material just prior to association with said rolls and releasable thereby just subsequent to removal from association with said punch, said last-named means dominating said energizing circuit.

13. For association with a plaster board form-

ing machine, means for cutting and perforating the plaster board as it emerges from said machine, comprising means positioned in the path of the emerging stream of unset plaster board and operative to cut such plaster board into lengths, means for moving each severed length away from said cutting means, a table, means receiving the severed length from such moving means and operative to advance the same over said table, a punch, and means to effect punching of such length of unset plaster board.

14. For association with a plaster board forming machine, means for cutting and perforating the plaster board as it emerges from said machine, comprising means positioned in the path of the emerging stream of unset plaster board and operative to cut such plaster board into lengths, means for moving each severed length away from said cutting means at an accelerated pace, a punch, means for moving each severed length of unset plaster board intermittently past said punch, and means to effect punching of such length of unset plaster board while such length is stationary.
